UNITED STATES PATENT OFFICE.

JOSEPH J. LEVESQUE, OF LEWISTON, MAINE.

AUTOMATIC TRAIN BRAKE.

Application filed July 26, 1923. Serial No. 654,003.

To all whom it may concern:

Be it known that I, JOSEPH J. LEVESQUE, a subject of the King of Great Britain, residing at Lewiston, in the county of Androscoggin and State of Maine, have invented certain new and useful Improvements in an Automatic Train Brake, of which the following is a specification.

This invention appertains to means for stopping a railroad train or the like, in case the same becomes derailed or leaves the track through any cause.

The primary object of the present invention is the provision of a novel device incorporated with the truck of a railroad car for automatically bleeding the air train pipe, when the train leaves the track for any cause, thereby automatically setting the brake and bringing the train to a halt.

Another prime object of the invention is the provision of novel means for incorporating the automatic device with a train truck, so that the same will be instantly operated when the truck leaves the rails.

A still further prime object of the invention is to provide an automatic train stop of the above character, which will be durable and efficient in use, one that will be simple and easy to manufacture, and one which can be placed upon the market and incorporated with a railroad car at a small cost.

With these and other objects in view, the invention consists in the novel construction, arrangement and formation of parts, as will be hereinafter more specifically described, claimed and illustrated in the accompanying drawings, in which drawings:

Figure 1 is a transverse section through a railroad car showing the improved automatic brake applying device incorporated therewith.

Figure 2 is a detail perspective view of one of the connecting arms for operating the connecting rod utilized for opening the train pipe when a car truck leaves the rails, and

Figure 3 is a detail perspective view of the valve handle pusher.

Referring to the drawings in detail, wherein similar references characters designate corresponding parts throughout the several views, the letter A generally indicates a railroad car and B the automatic means for applying the train brake, in case the car becomes derailed through any reason. The

car A can be considered of any character now commonly in use, and as shown consists of the body 5 including the floor 6, the supporting bolster 7 and the truck 8. The truck carries any preferred type of journal boxes 9 for supporting the car axle 10, to which are secured the car wheels 11, which are adapted to engage the railroad car track 12.

The air brake line or train pipe 16 extends longitudinally of the train and operates the brakes (not shown) in the usual way, when air is released therefrom. As shown the air train pipe 15 supports a depending valve structure 16 and this valve structure is provided with oppositely extending operating handles 17 and 18 and it is obvious that when these valve handles are rotated that the valve will be opened to permit the bleeding of the train pipe 15 and thus bring about the automatic setting of the brake.

The means B for bringing about the automatic setting of the brake by the bleeding of the air train pipe 15 comprises a pair of axle operating members 20 and 21, which engage the axle adjacent to the opposite terminals thereof. These axle engaging members 20 comprise a standard 22 and a depending loop head 23, which rotatably and loosely receives the axle 10. The upper end of the post 22 can be reduced to provide a threaded stud 24, the purpose of which will be hereinafter more fully described. The threaded studs 24 are inserted through suitable openings formed in the outer terminals of oppositely directed crossed operating connecting rods 25 and 26 and the studs are held in place by suitable retaining nuts or the like 27. The opposite terminals of the connecting rods 25 and 26 from the terminals which are connected with the axle engaging members 20 and 21 are pivotally connected as at 28 to depending supporting posts 29 which can be secured to the car body 5 in any preferred way. The connecting rods 25 and 26 at a point intermediate their ends carry depending valve handle pushers 30 each of which includes a body 31 having the lower end thereof provided with a slot 32 for receiving the valve handles 17 and 18.

The upper ends of the bodies 31 are provided with threaded studs 33 which are extended through their respective connecting rods 25 and 26 and these studs can be held in place by suitable nuts or the like 34.

In order to normally maintain the axle

operating members 20 and 21 in their raised position, each of the connecting rods 25 and 26 have secured thereto contractile coil springs 35, which are in turn connected to 5 suitable hooks 36 carried by the depending supporting members 29. In use of the improved device, it can be seen that as soon as the car wheels leave the track through any cause, the axle will tend to move from out of 10 its usual position, which will instantly operate the rods 21 and 20. These members 20 and 21 will in turn impart their movement to the connecting rods 25 and 26, and operate the valve-handles 17 and 19 and thus open the 15 train pipe and permit the bleeding thereof. This of course will bring about the setting of the brake.

From the foregoing description, it can be seen that I have provided an exceptionally 20 simple and compact arranged device for automatically setting the brakes of a train, when a train or any portion thereof leaves the rails through any cause.

Changes in details may be made without 25 departing from the spirit or the scope of this invention.

What I claim as new is:

1. In an automatic train brake, the combination with a railroad train including a 30 car body, a car truck including an axle and car wheels, and an air train pipe extending longitudinally of the car having a depending air bleeding valve connected therewith

including an operating handle, of a brake applying device comprising depending arms 35 receiving the axle, crossed connecting rods extending transversely across the entire width of the body pivotally secured at one of their ends to the car body and connected at their opposite ends to the axle engaging 40 arms and means connecting the connecting rods with the handle of the valve.

2. In an automatic train brake, a railroad car including a body, a truck having a rotatable axle and car wheels, a longitudinally 45 extending air train pipe carried by the body having a depending bleed valve connected therewith, operating handles for the valve, of a brake applying device comprising a 50 pair of depending arms, loops formed on the lower ends of the arms for receiving the axle, diagonally extending cross connecting rods having their outer terminals secured to the arms, means pivotally securing the inner terminals of the connecting rods to the car body, valve handle pushers secured to the connecting rods at a point intermediate their 55 ends, and engaging said valve handles, and resilient means for normally holding the connecting rods in a raised position.

In testimony whereof I affix my signature in presence of two witnesses.

JOSEPH J. LEVESQUE.
